US00D674404S

(12) **United States Design Patent**
Pearcy et al.

(10) **Patent No.:** **US D674,404 S**
(b5) **Date of Patent:** **** Jan. 15, 2013**

(54) **COMPUTER HAVING GRAPHICAL USER INTERFACE**

(75) Inventors: **Derek Patton Pearcy**, San Francisco, CA (US); **Jessica J. Gaskins**, Boulder Creek, CA (US)

(73) Assignee: **McAfee, Inc.**, Santa Clara, CA (US)

(**) Term: **14 Years**

(21) Appl. No.: **29/404,938**

(22) Filed: **Oct. 26, 2011**

(51) LOC (9) Cl. **14-04**

(52) U.S. Cl. **D14/486**

(58) Field of Classification Search **D14/485, D14/486, 487, 488, 489, 490, 491, 492, 493, D14/494, 495; D18/26, 31, 32, 33; D19/6, D19/52; D20/11, 12, 23, 24, 25, 29, 30, D20/31, 32, 36, 37, 38; 715/700, 706, 716, 715/719, 810, 784, 789, 792, 835, 836, 837, 715/839, 840, 846, 847, 973, 974, 975**

See application file for complete search history.

(57) **CLAIM**

The ornamental design for a computer having graphical user interface, as shown and described.

DESCRIPTION

FIG. 1 is a perspective front view of a first embodiment of a computer having graphical user interface according to the present design;

FIG. 2 is a front view thereof;

FIG. 3 is a perspective front view of a second embodiment of a computer having graphical user interface according to the present design; and,

FIG. 4 is a front view thereof.

The computer shown in broken lines form no part of the claimed design.
